(57) **CLAIM**

The ornamental design for a portable display device as shown and described.

DESCRIPTION

FIG. 1 is a front left perspective view of a portable display device showing my new design;

FIG. 2 is another front left perspective view of the portable display device;

FIG. 3 is a front elevational view of the portable display device, showing a graphic;

FIG. 4 is a rear elevational view of the portable display device;

FIG. 5 is a left side elevational view of the portable display device;

FIG. 6 is a right side elevational view of the portable display device;

FIG. 7 is a top plan view of the portable display device;

FIG. 8 is a bottom view of the portable display device;

FIG. 9 is an enlarged view of the portable display device, taken from encircled portion 9 in FIG. 2;

FIG. 10 is an enlarged view of the portable display device, taken from encircled portion 10 in FIG. 2; and,

FIG. 11 is an enlarged view of the portable display device, taken from encircled portion 11 in FIG. 8.

The broken lines in the drawings depict portions of the portable display device and form no part of the claimed design. The dashed broken lines in FIGS. 3 and 4, representing text, depict environmental subject matter only and form no part of the claimed design. The dot-dash-dot broken lines in FIGS. 2 and 8-11 depict enlarged views only and form no part of the claimed design.

1 Claim, 6 Drawing Sheets
